US0D1026205S

(12) **United States Design Patent** (10) **Patent No.:** **US D1,026,205 S**
(45) **Date of Patent:** **** May 7, 2024**

(54) **MODULAR INHALER ADHERENCE MONITOR**

(71) Applicant: **Reciprocal Labs Corporation**, Madison, WI (US)

(72) Inventor: **Samuel A. Koblenski**, Madison, WI (US)

(73) Assignee: **Reciprocal Labs Corporation**, San Diego, CA (US)

(**) Term: **15 Years**

(21) Appl. No.: **29/800,865**

(22) Filed: **Jul. 23, 2021**

(51) LOC (14) Cl. **24-04**

(52) U.S. Cl.

USPC **D24/110**

(58) **Field of Classification Search**

(57) **CLAIM**

The ornamental design for a modular inhaler adherence monitor, as shown and described.

DESCRIPTION

FIG. 1 is a front, top perspective view of a modular inhaler adherence monitor;

FIG. 2 is a bottom, rear perspective view of a modular inhaler adherence monitor;

FIG. 3 is a side view of the modular inhaler adherence monitor;

FIG. 4 is a front view of the modular inhaler adherence monitor;

FIG. 5 is opposite side view of the modular inhaler adherence monitor;

FIG. 6 is a back view of the modular inhaler adherence monitor;

FIG. 7 is a top view of the modular inhaler adherence monitor; and,

FIG. 8 is a bottom view of the modular inhaler adherence monitor.

1 Claim, 4 Drawing Sheets
